UNITED STATES PATENT OFFICE.

FRANK A. HALLECK, OF CHICAGO, ILLINOIS, ASSIGNOR TO SULLIVAN MACHINERY COMPANY, A CORPORATION OF MASSACHUSETTS.

DRILLING APPARATUS.

Application filed February 19, 1923. Serial No. 619,835.

My invention relates to drilling apparatus.

It has for its object to provide an improved drilling apparatus. A further object of my invention is to provide such an apparatus which is especially and conveniently adapted to use in oil well or similar drilling practice and which at the same time is capable of drilling to great depths, the same comprising an improved apparatus which is very compactly and powerfully built and also conveniently arranged and controlled. A still further object of my invention is to provide such an apparatus of the core drill type which is especially adapted to oil well or similar drilling practice at great depths. These and other objects and advantages of my improved construction will, however, hereinafter more fully appear.

In the accompanying drawings, I have shown for purposes of illustration one embodiment which my invention may assume in practice.

25 In these drawings,—

Fig. 1 is a front elevation of the apparatus in position over a hole, the drill rods being omitted.

30 Fig. 2 is a side elevation of the apparatus in the same position.

Fig. 3 is a side elevation from the opposite side of the apparatus.

35 Fig. 4 is a detail view showing the interlocking connection between certain control rods.

Fig. 5 is a plan view partially in section of the apparatus shown in Fig. 1.

40 Fig. 6 is a rear elevation partially in section of the apparatus, certain parts being broken away to show the transmission mechanism.

45 In this illustrative construction, while it will be evident that other feeding mechanism may be used, I have shown my invention applied to a well known Sullivan type of hydraulically fed core drilling mechanism including a usual feed cylinder 1 having usual water connections, usual rod connections 2 and 3 and a clamp 4 adapted to receive the drill rods and permit the same to be rotated or passed upwardly or downwardly through the mechanism, this drilling

mechanism being mounted and driven in an improved manner hereinafter described.

55 Referring more particularly to my improved construction, it will be noted that a trackway 5 having longitudinally disposed slots 6 therein is carried on a support 7, herein in the form of cross ties, and that this track carries a frame indicated generally at 8 which in turn carries the complete drilling mechanism, suitable guiding shoes 9 being provided on the bottom of the frame to engage the tracks 5 and fit over the upper surface thereof as shown, the frame 8 being held in any desired relation on the track 5 by bolt connections 10 which when released are movable longitudinally in the slots 6 in such manner as to enable the frame 8 to be adjusted into any desired position upon the tracks. If desired the frame 8 may be adjusted manually longitudinally of the trackway or adjusted by power through any suitable means, but I prefer to provide for power movement of the frame by hydraulic means, the same preferably being connected as hereinafter described, to the same source of water which supplies water to the hydraulic cylinder 1. As shown, I also provide a cylinder 11 fixed to the bottom of the frame 8 and having therein a cooperating piston 12 provided with a rod 13 fixed at 14 to the rearmost tie 7, the water flow connections 15 being of any usual form adapted to supply water to the opposite sides of the piston 12 in such manner as to cause the frame 8 to move longitudinally of the trackway in either direction desired.

60 Referring more particularly to the frame 8 and the mechanism thereon, it will be noted that this frame is of a very strong and rigid construction including parallel pieces of structural steel 16 connected together at their top and bottom, the construction being such that from the ends of the members 16 access may be readily had to the nuts on top of the bolt connections 10 to enable release or tightening of these connections when desired. More particularly, it will be noted that four standards 17 each herein in the form of a plurality of angle irons connected with their webs, together are supported on the members 16 in such manner as to form a rectangular hollow frame and that these members 17 are

connected at the bottom and top by tie members 18 and braced by suitable braces 19 and 20, the construction resulting in an exceedingly strong and rigid frame well adapted 5 to support the drilling mechanism and to withstand the strains and stresses incident to the operation of the latter and to longitudinal shifting on the trackway through the powerful hydraulic shifting means previously described.

Upon the top of this frame 8 is the vertical drilling apparatus including the cylinder 1, the mechanism here being supported on a suitable frame 21 rigidly connected to 15 base frames 23 and 24 of which the base frame 23 carries one of the supporting standards 25 of a hoist drum 26 disposed on an axis extending transversely of the trackway in rear of the cylinder 1, while the base 20 frame 24 supports the other drum standard 27 and also supports a suitable driving motor 28. Referring more particularly to the latter, it will be noted that the same is herein in the form of a steam engine of the 25 angle type having one cylinder 29 disposed horizontally and longitudinally of one edge of the frame 8 and another cylinder 30 disposed vertically at the rear of the engine in such manner as to bring its crank shaft at 30 the rear of the frame, the cylinders carrying their usual pistons and being controlled by usual valve gear and supplied through pipe connections 31 with steam from a boiler (not shown) usually accompanying such an outfit.

Operatively connected to this engine 28 are the driving connections for rotating the rotating members 2 and 3 of the drilling apparatus. More particularly, it will be noted that, as shown in Fig. 6, the engine shaft 32 40 has keyed thereto a sleeve 33 on a pinion 34 and that this sleeve is journaled in suitable bearings 35 and provided with a bore within the pinion adapted to receive a cylindrical end 36 of a cross shaft, generally indicated at 37, suitably journaled in the frame. As shown, the adjacent portion of this shaft is a hexagonal portion 38 carrying a clutch member 39 in the form of a pinion having internal teeth 40 and external 45 teeth 41 and adjustable longitudinally of the hexagonal portion to bring the internal teeth into or out of mesh with the teeth of the pinion 34 or the external teeth into or out of mesh with a larger spur gear 42 keyed 50 on a parallel transverse shaft 43 suitably journaled in the frame and rotated by a larger spur gear 44 keyed to the shaft and constantly meshing with the pinion 34, the member 39 being adjusted by a suitable 55 clutch shipper 45 adjustable by mechanism hereinafter described. Carried adjacent the member 39 and likewise fixed to and rotatable with the hexagonal portion 38 of the shaft 37 is also a still larger spur gear 46 60 which in turn meshes with a pinion 47 simi-

lar to the member 39 and splined on the shaft 43 and movable longitudinally thereof into or out of engagement with the gear 46 by means of a clutch shipper 48. Thus, it will be noted that shifting the pinion 39 70 into engagement with the pinion 34 directly connects the engine to the shaft 37, while sliding the pinion 39 to the right meshes it with gear 42 and causes a drive through the gears 34, 44, 42, and member 39, giving a 75 slower speed. Further, by throwing the gear 47 to the right as shown in Fig. 6, a still lower speed is obtainable. As shown, the shaft 37 also has a cylindrical portion 49 thereon on which is keyed a bevel pinion 50 meshing with a bevel gear 51 carried on the rear end of a longitudinally extending shaft 52 (see Fig. 2) which in turn is connected through bevel gearing 53 to the rotating parts of the drilling mechanism, a usual 80 clutch 54 also being provided to enable disconnection of the rotating mechanism from its driving mechanism when desired and this clutch preferably also has a shear pin 55 between one of its elements and the shaft to 85 prevent breakage under severe operating conditions.

Operatively connected to the shaft 37 is also the drum driving mechanism for the drum 26, the same herein preferably including a usual form of friction clutch generally indicated at 56 and controlled by a suitable shipper 57 to control the connection of a member 58 keyed to the shaft and a member 59 rotatable on the shaft and connected to a sleeve pinion 60 meshing with an external gear 61 disposed coaxially with the drum 26 and located at one end thereof. Thus, it will be noted that by adjusting the shipper mechanism 57 it is made possible to drive the 100 drum 26 through frictional controlling mechanism and regulate the movement thereof as desired. In the particular form of my invention shown, it will be noted that the member 58 of the clutch mechanism 56 105 carries a ring 62 between which and the shipper 57 a plurality of suitable lever mechanisms 63 are connected as shown, the ring being adapted to be held in different 110 positions by a set screw 64. As also shown, one of the elements of each lever mechanism engages with a plate 65 to press the same into contact with an internally extending annular member 66 on the external clutch member 59, the movement of the latter being 115 in turn controlled by a brake band 67 operatively connected to a plurality of spring pressed plungers or lifters 68 normally acting to keep the brake band from the brake wheel. Attention should here also be directed to the fact that through the clutch 56 it is made possible to rotate the drum 26 not only during rotation of the drilling mechanism but independently of the rotation of the latter without in any wise affect- 120 125 130

ing the rotation of the drilling mechanism.

Operatively connected to the shaft 37 and herein more particularly through the shaft 43 geared thereto, is suitable capstan mechanism used for winding purposes and including capstans 69, usually called "nigger heads" or "cat heads". As shown, these members are carried on the opposite ends of a transverse shaft 70 having a spur gear 71 thereon adjustable longitudinally of the shaft by a suitable shipper 72 into or out of engagement with a spur gear 73 keyed on the adjacent end of the shaft 43, the construction being such that the rotation of the shaft 70 is controlled by the shifting of the gear 71 previously described. Attention is also directed to the fact that each of these nigger or cat heads is provided with a brake band 74 controllable by a suitable brake lever 75, the brake band and control lever being herein for example located adjacent the head or drum. As shown a suitable lever 76 at the rear of the machine is also provided to adjust the shipper 72.

In connection with the driving mechanism thus far described and extending transversely across the rear of the frame, attention is directed to the fact that the whole transmission mechanism including the change speed is enclosed in a suitable casing 77 adapted to be substantially filled with lubricant in such manner as to maintain a lubricant supply to all the gearing. It will also be noted that a suitable oil pump 78 of any well known construction is provided operatively connected to a moving part of the motor, herein to the crank shaft thereof, which operates to maintain a flow of lubricant to all the necessary parts of the apparatus including the engine, drum and drilling mechanism through connections not shown.

Operatively associated with the mechanism just described is also improved controlling mechanism. This mechanism is so far as possible preferably located at the front right hand corner of the mechanism in such an arrangement as to be most readily accessible to the driller superintending the drilling operation. More particularly, it includes a lever 79 suitably pivoted on a horizontal axis at 80 and pivotally connected through a lever connection 81 to a rod 82 controlling the operation of the friction clutch. It further includes levers 83, 84 pivoted on a common horizontal axis adjacent their inner ends and having shorter arms connected at 85 and 86 to rods 87, 88 which in turn lead to bell cranks 89, 90 connected through connections not shown to the shippers 45, 48 for the gears 39, 47. In order to prevent simultaneous connection of these gears, it will also be noted that an interlock is provided, a sliding pin 91 being disposed in a suitable recess in a boss formed on the standard 25 between the rods 87, 88 and adapted

to cooperate with notches 92, 93 in the latter in such manner as automatically to enter the notch in one rod and automatically prevent operation thereof during the operation of the other rod. Adjacent these other levers is a lever 94 pivoted at 95 and adapted to control the connection of the clutch 54. Moreover, it will be noted that a lever 96 pivoted at 97 is connected to the clutch brake band through a usual eccentric connection. As for the drill feeding mechanism, this is controlled through a suitable control lever 98 likewise accessible from the same corner of the front end of the frame, while the speed of the motor is controlled by a throttle lever 99 similarly located. Here it will also be noted that the lever 98 controls the water supply to the cylinder through a 4-way valve 100, suitably connected to the cylinder and the water inlet and outlet, while the water supply to the cylinder 1 and cylinder 11 is controlled by a lever 101 in turn controlling a four-way valve 102 connected to the inlet and discharge pipes for the cylinder 1 and similarly connected to cylinder 11 and a suitable source of supply.

In the operation of my improved machine, it is possible to move the drill back from the hole whenever desired by shifting the frame 8 relative to the trackway 5 through the hydraulic feeding mechanism, the parts being capable of being clamped in any desired position by the bolt connections 10. Moreover, it will be noted that due to the disposition of the drum 26, the drum is enabled to wind on without difficulty in any position of the frame 8 relative to the trackway. As for the drilling mechanism, it will be observed that the same may be rotated at any one of a plurality of speeds, herein three, to adapt it to varying conditions, while the feed thereof may obviously be varied over the usual wide range possible with a hydraulic feeding mechanism, my improved feeding mechanism herein being preferably of a well known Sullivan type. It will also be evident that the changes in speed may be utilized in connection with the drum and that other variations in speed may be obtained through the friction clutch 56 controlling the connection of the latter and that this clutch and the clutch 54 may be disconnected when desired to enable simultaneous operation of the drum and controlling mechanism, or independent operation of either, each of the clutches also being releasable upon overload in such manner as to protect the mechanism from breakage. Attention is also directed to the control of speed herein made possible in the use of the nigger heads or cat heads through the independent braking mechanism for each head. Here it will also be observed that these heads are conveniently located for operations in handling casing, rods, or the like through co-

operation if need be with the drum 26. As for the control mechanism, it will be particularly noted that this mechanism is especially conveniently located relative to the 5 most desirable position for the operator, namely at the front right hand side of the machine, the disposition of the controls being such that the operator may adjust every mechanism except the cat head mechanism 10 from this station.

As a result of my improved construction it will be observed that an exceedingly rugged mechanism is provided whereby through my improved arrangement of parts 15 the different needed elements are so located as to perform their functions most effectively and at the same time present an exceedingly compact mechanism of great strength especially adapted to use in deep holes, al- 20 though obviously it is not limited to such use. Attention is also directed to the fact that by my improved arrangement of parts and more particularly my improved disposition of the control mechanism, it is made 25 possible for the operator to control all the various mechanisms quickly and easily when and as needed without necessitating his leaving his post near the drill hole. Moreover, through the use of the shiftable frame, it 30 will be noted that the entire mechanism may be moved away from the drill hole as is found to be highly desirable in well drilling practice and that this movement may be obtainable whenever the operator desires and 35 quickly and easily through the hydraulic mechanism. These and other advantages of my improvement will, however, be clearly apparent to those skilled in the art.

While I have in this application specifically described one form which my invention may assume in practice, it will be understood that this form of the same is shown for purposes of illustration and that the invention may be modified and embodied in various 45 other forms without departing from its spirit or the scope of the appended claims.

What I claim as new and desire to secure by Letters Patent is:

1. In a drilling apparatus, a supporting 50 base having a substantially horizontal guideway, a frame slidably guided on said base, hole drilling mechanism carried on said frame and including drill rod rotating mechanism and power operated feeding mechanism for axially feeding the drill rod, and means actuated from the same power source as said feeding mechanism for adjusting said frame and drilling mechanism bodily laterally relative to the guideway on said base 55 and transversely relative to the drill hole.

2. In a drilling apparatus, a supporting base, a frame slidably guided on said base, hole drilling mechanism carried on said frame including drill rod rotating mechanism and hydraulic feeding mechanism for

axially feeding the drill rod, and means including manually controlled hydraulic mechanism connected to the same power source as said feeding mechanism for adjusting said frame and drilling mechanism 70 bodily relative to said base and transversely relative to the drill hole.

3. In a drilling apparatus, a supporting base, a frame slidably guided thereon, hole drilling mechanism carried on said frame 75 including drill rod rotating mechanism and hydraulic feeding mechanism for axially feeding the drill rod, and manually controlled power operated means connected to the same power source as said feeding mech- 80 anism for adjusting said frame and hole drilling mechanism relative to said base and transversely relative to the drill hole, said adjusting means including a hydraulic cyl- 85 inder on one element and a cooperating pis- ton on the other.

4. In a drilling apparatus, a supporting base presenting a trackway, a frame slidably guided on said trackway, hole drilling mech- 90 anism carried on said frame and including drill rod rotating mechanism and power op- erated feeding mechanism for axially feed- 95 ing the drill rod, and power driven means connected to the same power source as said feeding mechanism for feeding said frame and drilling mechanism relative to said base and transversely relative to the drill hole into any desired position upon said track- 100 way, said feeding means including manual controlling mechanism adjustable to vary the rate and speed of feed as desired.

5. In a drilling apparatus, a supporting base presenting a trackway, a frame slidably guided on said trackway, hole drilling mech- 105 anism carried on said frame and including drill rod rotating mechanism, hoisting mech- 110 anism on said frame including a hoisting drum rotatable on an axis extending trans- versely of the longitudinal axis of said frame, and power operated means for moving said frame and drilling mechanism relative to said base and transversely relative to the drill hole into any desired position upon said trackway, said moving means in- 115 cluding controlling mechanism operable from the drill operator's station.

6. In a drilling apparatus, a supporting base presenting a trackway, a frame slidably guided on said trackway, hole drilling mech- 120 anism carried on said frame including drill rod rotating mechanism and hydraulic feed- 125 ing mechanism for axially feeding the drill rod, and hydraulic means connected to the same power source as said feeding mech- anism for moving said frame and drilling mechanism relative to said base and trans- versely of the drill hole into any desired position upon said trackway, said hydraulic means including controlling mechanism op- 130 erable from the drill operator's station.

7. In a drilling apparatus, a supporting base presenting a trackway, a frame slidably guided on said trackway, hole drilling mechanism carried on said frame and including 5 drill rod rotating mechanism and power operated feeding mechanism for axially feeding the drill rod, and manual controllable power driven mechanism connected to the same power source as said feeding mechanism 70
- 10 nism for adjusting said frame and drilling mechanism relative to said base comprising cooperating elements carried by said base and frame in the space between the elements of said trackway.
- 15 8. In a drilling apparatus, a supporting base presenting guideways, an upstanding frame movable on said guideways transversely relative to the drill hole, hole drilling mechanism carried on said frame including 80
- 20 drill rod rotating mechanism and hydraulic feeding mechanism for axially feeding the drill rod, and a hydraulically operated operative connection connected to the same power source as said feeding mechanism and disposed between the bottom of said frame and 85
- 25 said base located between said guideways for adjusting said frame and drilling mechanism longitudinally of said guideways. 90
9. In a drilling apparatus, a supporting 95
- 30 base presenting guideways, an upstanding frame movable on said guideways transversely relative to the drill hole, hole drilling mechanism carried on the top of said frame and including drill rod rotating mechanism
- 35 and hydraulic feeding mechanism for axially feeding the drill rod, and an operative connection between said frame and said guideways disposed longitudinally of said base for shifting said frame relative to the latter 100
- 40 and including a hydraulic cylinder carried by one of said elements and a piston carried by the other, said hydraulic shifting means being connected to the same power source as said feeding mechanism.
- 45 10. In a drilling apparatus, a supporting base having parallel slides thereon, a frame slidably mounted on said slides, hole drilling mechanism carried on said frame including drill rod rotating mechanism and 105
- 50 power operated feeding mechanism for axially feeding the drill rod, and operative connections between said base and said frame whereby the frame and drilling mechanism may be bodily adjusted longitudinally of 110
- 55 said slides and transversely relative to the drill hole, said adjusting means including shifting mechanism connected to the same power source as said feeding mechanism and disposed substantially centrally between and 115
- 60 parallel to said slides. 120
11. In a drilling apparatus, a supporting base presenting guideways, a frame slidably mounted on said guideways, a hole drilling mechanism carried on said frame including 125
- 65 hoisting mechanism having a drum movable with said frame and rotatable on an axis extending transversely of the longitudinal axis of the latter and a motor likewise movable with said frame and driving said drilling mechanism and said drum, and means 70
- for moving said frame and drilling mechanism relative to said base including an element secured to the latter and cooperating with an element movable with said frame. 75
12. In a drilling apparatus, a supporting base presenting parallel longitudinally extending guideways, a frame slidably mounted on said guideway, power operated mechanism for shifting said frame longitudinally on said guideway, drill rod rotating 80
- mechanism on said frame, hoisting mechanism on said frame including a drum on said frame adjacent said rotating mechanism and rotatable on an axis disposed transversely of the longitudinal axis of said frame, a motor 85
- on said frame, and operative connections between said motor and said rotating mechanism and drum comprising a power shaft arranged parallel with said drum axis, and a transmission shaft arranged longitudinally 90
- of said frame. 95
13. In a drilling apparatus, a support presenting a guideway, a frame adjustable longitudinally of said guideway toward and from the drill hole, power operated means for shifting said frame longitudinally relative to said support, drill rotating mechanism on said frame, hoisting mechanism including a hoisting drum immediately adjacent said rotation mechanism and rotatable 100
- on an axis disposed transversely of the longitudinal axis of said frame, and a motor on said frame operatively connected to said rotation mechanism and drum. 105
14. In a drilling apparatus, a frame, drill rotating mechanism thereon, a hoisting drum on said frame immediately adjacent said rotating mechanism and rotatable on an axis disposed transversely of the longitudinal axis of said frame, a motor on said frame, a motor on said frame, 110
- and motor driven variable speed transmission mechanism on said frame selectively connectible to drive either said rotation mechanism or said drum. 115
15. In a drilling apparatus, a frame, drill rotating mechanism thereon, a hoisting drum on said frame immediately adjacent said rotating mechanism and rotatable on an axis disposed transversely of said frame, a motor on said frame, and motor driven transmission mechanism on said frame driving said rotation mechanism or said drum and selectively operative to drive said rotation mechanism at any of a plurality of predetermined speeds. 120
16. In a drilling apparatus, a frame, drill rotating mechanism thereon, a hoisting drum on said frame immediately adjacent said rotating mechanism and rotatable on an axis disposed transversely of said frame, a mo- 125
- 130

tor on said frame, and motor driven transmission mechanism on said frame selectively operable to drive either said rotation mechanism or said drum at any of a plurality of predetermined speeds.

17. In a drilling apparatus, a frame, drill rotating mechanism thereon, a hoisting drum on said frame immediately adjacent said rotating mechanism and rotatable on an axis 10 disposed transversely of the longitudinal axis of said frame, a motor on said frame, and motor driven variable speed transmission mechanism on said frame including a transverse motor shaft operatively connected 15 to said rotation mechanism and said drum.

18. In a drilling apparatus, a frame, drill rotating mechanism thereon, a hoisting drum on said frame immediately adjacent said rotating mechanism and rotatable on an axis 20 disposed transversely of the longitudinal axis of said frame, a motor on said frame, and motor driven transmission mechanism on said frame including a transverse motor shaft parallel with said drum axis operatively connected to said drum and a longitudinal shaft operatively connected to said 25 rotation mechanism and motor shaft and extending beneath said drum.

19. In a drilling apparatus, a frame, drill 30 rotating mechanism thereon, a hoisting drum on said frame immediately adjacent said rotating mechanism and rotatable on an axis disposed transversely of the longitudinal axis of said frame, a motor on said frame, and motor driven transmission mechanism on said frame including a transverse motor shaft parallel with said drum axis and operatively connected to said drum, a shaft 35 extending longitudinally of said frame and operatively connected to said rotation mechanism and motor shaft and extending beneath said drum, and change speed mechanism on said frame selectively connectible 40 to drive said drum or rotation mechanism 45 at a plurality of speeds.

20. In a drilling apparatus, a frame, drilling mechanism on said frame, hoisting mechanism on said frame including a drum immediately adjacent said drilling mechanism 50 and rotatable on an axis disposed transversely of the longitudinal axis of said frame, and a motor on said frame disposed substantially within the longitudinal limits of said drilling mechanism and drum and 55 having a power shaft disposed parallel with said drum axis and operatively connected to each of the same.

21. In a drilling apparatus, a frame, drilling mechanism thereon, hoisting mechanism 60 in rear of said drilling mechanism and including a drum rotatable on an axis disposed transversely of the longitudinal axis of said frame, and a motor on said frame disposed longitudinally of the latter at one 65 side of said drum and having a power shaft

disposed parallel with said drum axis and operatively connected to said drilling mechanism and drum, the axis of said drum intersecting said motor.

22. In a drilling apparatus, drill rotating 70 mechanism, a motor, and transmission mechanism between said motor and rotating mechanism including a shaft operatively connected to the latter, a plurality of shafts disposed transversely relative to said shaft 75 operatively connected to said shaft and to the motor, and change speed gearing on said transversely disposed shafts whereby the speed of said first mentioned shaft may be varied.

23. In a drilling apparatus, drill rotating mechanism, hoisting mechanism, a motor, and transmission mechanism between said motor and mechanisms including a shaft operatively connected to the rotating mechanism and a plurality of shafts disposed transversely relative to said shaft one of which is operatively connected to said shaft, motor, and hoisting mechanism, and change speed mechanism between said transversely disposed shafts whereby the speed of said last mentioned transverse shaft may be varied.

24. In a drilling apparatus, drill rotating mechanism, hoisting mechanism, a motor, and transmission mechanism between said motor and mechanisms including a shaft operatively connected to the rotating mechanism, a plurality of operatively connected shafts disposed transversely relative to said shaft and one of which is operatively connected to said shaft, motor, and hoisting mechanism, change speed mechanism between said transverse shafts whereby the speed of said last mentioned transverse shaft may be varied, a clutch controlling the rotation of 100 said rotating mechanism, and a clutch between said hoist driving shaft and the hoisting mechanism.

25. In a drilling apparatus, drill rotating mechanism, hoisting mechanism, a motor, and transmission mechanism between said motor and mechanisms including a shaft operatively connected to the rotating mechanism, a plurality of operatively connected shafts disposed transversely of said shaft 110 and one of which is operatively connected to said shaft, motor, and hoisting mechanism, change speed mechanism between said transverse shafts whereby the speed of said last mentioned transverse shaft may be varied, a clutch including an overload releasing element controlling the rotation of said rotating mechanism, and a friction clutch between said hoist driving shaft and the hoisting mechanism.

26. In a drilling apparatus, drill rotating mechanism, hoisting mechanism including a drum, a motor, and transmission mechanism between said motor and mechanisms including a shaft operatively connected to the rotat- 120 125

- ing mechanism, a plurality of operatively connected shafts disposed transversely relative to said shaft and one of which is operatively connected to said shaft, motor, and hoisting mechanism and also disposed parallel to the drum axis, change speed mechanism between said transverse shafts whereby the speed of said last mentioned transverse shaft may be varied, a clutch controlling the rotation of said rotating mechanism, and a clutch controlling the rotation of said hoisting mechanism.
27. In a drilling apparatus, a frame, drill rotating mechanism thereon, hydraulic drill feeding mechanism on said frame, a hoisting drum on said frame in immediate adjacency to said rotation and feeding mechanisms and rotatable on an axis disposed transversely of the longitudinal axis of said frame, a capstan on said frame and likewise rotatable on a transverse axis parallel with said drum axis, and a motor on said frame operatively connected to said rotation mechanism, said drum, and said capstan.
28. In a drilling apparatus, a frame drill rotating mechanism thereon, a hoisting drum on said frame in immediate adjacency to said rotation mechanism and rotatable on an axis disposed transversely of the longitudinal axis of said frame, a capstan on said frame and likewise rotatable on a transverse axis parallel with said drum axis, a motor on said frame, and change speed mechanism driven thereby selectively connectible to said rotation mechanism, said drum, or said capstan.
29. In a drilling apparatus, a frame, drill rotating mechanism thereon, a hoisting drum on said frame in immediate adjacency to said rotation mechanism and rotatable on an axis disposed transversely of the longitudinal axis of said frame, a motor having a transverse power shaft parallel with said drum axis, reduction mechanism between said shaft and said drum, and change speed mechanism between said reduction mechanism and said motor connectible to said rotation mechanism or to said reduction mechanism.
30. In a drilling apparatus, a frame, drill rotating mechanism thereon, a hoisting drum thereon in immediate adjacency to said rotating mechanism and rotatable on an axis disposed transversely of the longitudinal axis of said frame, a motor having a transverse power shaft parallel with said drum axis, reduction mechanism between said shaft and said drum, change speed mechanism between said reduction mechanism and said motor connectible to said rotation mechanism or to said reduction mechanism.
31. In drilling apparatus, a frame, drill rotating mechanism thereon, a hoisting drum
- thereon in immediate adjacency to said rotating mechanism and rotatable on an axis disposed transversely of the longitudinal axis of said frame, a motor having a transverse power shaft parallel with said drum axis, reduction mechanism between said shaft and said drum, change speed mechanism between said reduction mechanism and said motor connectible to said rotation mechanism or to said reduction mechanism, 70 and mechanism likewise driven through said change speed mechanism and including a capstan on each side of said frame rotatable on a transverse axis.
32. In a drilling apparatus, drill rotating mechanism, a motor, transmission mechanism between said motor and rotating mechanism including a shaft operatively connected to the latter, a plurality of shafts disposed transversely relative to said shaft and operatively connected thereto and to the motor including a shaft operatively connected to said first mentioned shaft and drum, change speed gearing between said transversely disposed shafts whereby the speed of said rotation mechanism and drum may be varied, and capstan mechanism driven through a portion of said change speed gearing.
33. In a drilling apparatus, drill rotating mechanism, a motor, transmission mechanism between said motor and rotating mechanism operatively connected to the latter and including a plurality of shafts disposed transversely relative to the longitudinal axis of the apparatus and operatively connected to said rotating mechanism and to the motor, change speed mechanism between said transversely disposed shafts operative to vary the rotation speed, and hoisting mechanism driven through said change speed mechanism.
34. In a drilling apparatus, drill rotating mechanism, a motor, transmission mechanism between said motor and rotating mechanism operatively connected to the latter and including a plurality of shafts disposed transversely relative to the longitudinal axis of the apparatus and operatively connected to said rotating mechanism and to the motor, change speed gearing between said transversely disposed shafts operative to drive said rotation mechanism at fast or slow speeds, and hoisting mechanism driven through said change speed gearing.
35. In a drilling apparatus, drill rotating mechanism, a motor, transmission mechanism between said motor and rotating mechanism operatively connected to the latter and including a plurality of shafts disposed transversely relative to the longitudinal axis of the apparatus and operatively connected to said rotating mechanism and to the motor, change speed gearing between said transversely disposed shafts, and hoisting

and capstan mechanism driven through said change speed gearing.

36. In a drilling apparatus, drill rotating mechanism, a motor, transmission mechanism between said motor and rotating mechanism operatively connected to the latter and including a plurality of shafts disposed transversely relative to the longitudinal axis of the apparatus and operatively connected 10 to said rotating mechanism and to the motor, change speed gearing between said transversely disposed shafts operative to drive said rotation mechanism at fast or slow speeds, and hoisting and capstan mechanism driven through a portion of said change speed gearing.

37. In a drilling apparatus, drill rotating mechanism, a motor, transmission mechanism between said motor and rotating mechanism 20 including a shaft operatively connected to the latter, a plurality of shafts disposed transversely relative to said shaft and operatively connected thereto and to the motor, change speed gearing between said transversely disposed shafts, and capstan mechanism driven through a portion of said change speed gearing including a plurality of independently controllable capstans.

38. In a drilling apparatus, drill rotating 30 mechanism, a motor, and transmission mechanism between said motor and rotating mechanism including a shaft operatively connected to the latter, a plurality of shafts disposed transversely relative to said shaft and operatively connected thereto and to the motor, change speed gearing between said transversely disposed shafts, and a lubricant filled casing enclosing said change speed gearing.

39. In a drilling apparatus, a frame, drill rotating mechanism on said frame, hoisting mechanism thereon including a drum rotatable on an axis extending transversely of the longitudinal axis of said frame, a motor 45 on said frame, and transmission mechanism between said motor and said rotating mechanism and drum including a driving connection for the rotating mechanism extending under said drum and change speed mechanism in rear of said drum connected thereto and to said driving connection.

40. In a drilling apparatus, a frame, drill rotating mechanism thereon, hoisting mechanism on said frame, a driving motor on 55 said frame, change speed mechanism between said motor and said mechanisms, and controlling means for said mechanisms including control members accessible from a point adjacent said rotating mechanism and operable from the drill operator's stand.

41. In a drilling apparatus, a frame, drill rotating mechanism thereon, hoisting mechanism on said frame, a driving motor on said frame, driving mechanism between said 60 motor and said mechanisms, hydraulic feed-

ing mechanism on said frame including controlling valve means, and controlling means for said rotating and hoisting mechanisms adjacent said last mentioned controlling means and operable from the drill operator's stand.

42. In a drilling apparatus, a frame, drill rotating mechanism thereon, hoisting mechanism on said frame, capstan mechanism on said frame, a driving motor on said frame, driving mechanism between said motor and said mechanisms, power operated feeding mechanism on said frame including controlling means, and controlling means for said rotating, hoisting, and capstan mechanisms adjacent said last mentioned controlling means and operable from the drill operator's stand.

43. In a drilling apparatus, a frame, drill rotating mechanism thereon, hoisting mechanism on said frame, a driving motor on said frame, driving mechanism between said motor and said mechanisms, hydraulic feeding mechanism on said frame including controlling means, and controlling means for said rotating and hoisting mechanisms adjacent said last mentioned controlling means, all of said controlling means being closely grouped and operable from the drill operator's stand.

44. In a drilling apparatus, a frame, drill rotating mechanism thereon, hoisting mechanism on said frame, change speed mechanism on said frame between said motor and said mechanisms, power operated feeding mechanism on said frame including controlling means, and controlling means for said rotating, hoisting and change speed mechanisms adjacent said last mentioned controlling means, all of said controlling means being closely grouped and operable from the drill operator's stand.

45. In a drilling apparatus, a frame, drill rotating mechanism thereon, hoisting mechanism on said frame, change speed mechanism on said frame between said motor and said mechanisms, hydraulic feeding mechanism on said frame including controlling means, and controlling means for said rotating, hoisting, and change speed mechanisms adjacent said last mentioned controlling means, all of said controlling means being closely grouped and operable from the drill operator's stand.

46. In a drilling apparatus, a guide way, a frame adjustable longitudinally thereof, drill rotating and hoisting mechanisms on said frame, a motor on said frame operatively connectible to said mechanisms, power driven frame adjusting means for moving said frame relative to said guideway, power driven feeding mechanism including controlling means, and control means for said rotating, hoisting and adjusting means adjacent said last mentioned controlling means,

all of said controlling means being closely grouped and operable from the drill operator's stand.

47. In a drilling apparatus, a guide way, 5 a frame adjustable longitudinally thereof, drill rotating and hoisting mechanisms on said frame, a motor on said frame operatively connectible to said mechanisms, hydraulic frame adjusting means for moving 10 said frame relative to said guideways, hydraulic feeding mechanism including controlling means, and control means for said rotating, hoisting and adjusting means adjacent said last mentioned controlling 15 means, all of said controlling means being closely grouped and operable from the drill operator's stand.

48. In a drilling apparatus, a frame, drill rotating mechanism thereon, hoisting mechanism on said frame, a driving motor on said 20 frame, transmission mechanism including change speed devices between said motor and said rotating and hoisting mechanisms, and controlling mechanism for said mechanisms including interlocking control mechanism for said change speed mechanism.

49. In a drilling apparatus, a frame, drill rotating mechanism thereon, hoisting mechanism on said frame, a driving motor on said 30 frame, transmission mechanism including change speed devices between said motor and rotating and hoisting mechanisms, and controlling mechanism for said mechanisms including interlocking control mechanism for 35 said change speed mechanism, each of said controlling mechanisms having an operating member accessible from a point adjacent said rotating mechanism and operable from the drill operator's stand.

50. Core drilling apparatus comprising a base presenting a trackway, a frame movable longitudinally thereof and transversely relative to the drill hole, drill rod rotating mechanism rigidly mounted on said frame, 45 hoisting mechanism carried on said frame, a motor carried on said frame, and operative connections between said motor and said rotating and hoisting mechanisms including change speed mechanism common to each 50 of said mechanisms, reduction mechanism peculiar to said hoisting mechanism, and a frictional controlling means controlling said drum.

51. Core drilling apparatus comprising a base presenting a trackway, a frame movable longitudinally thereof and transversely relative to the drill hole, drill rod rotating mechanism mounted on said frame, hoisting mechanism carried on said frame, a motor 60 carried on said frame, operative connections between said motor and said rotating and hoisting mechanism, hydraulic drill rod feeding mechanism, and hydraulic mechanism connected to the same supply for feeding 65 said frame longitudinally of said trackway.

52. In a drilling apparatus comprising a base presenting a trackway, a frame movable longitudinally thereof and transversely relative to the drill hole, drilling mechanism including hydraulic drill controlling mechanism on said frame, and frame feeding mechanism including hydraulic controlling mechanism operatively connected to said first mentioned hydraulic controlling mechanism. 70

53. In a drilling apparatus comprising a base presenting a trackway, a frame movable longitudinally thereof and transversely relative to the drill hole, drilling mechanism including hydraulic drill controlling mechanism on said frame, and frame feeding 80 mechanism including hydraulic controlling mechanism operatively connected to said first mentioned hydraulic controlling mechanism, each of said hydraulic controlling mechanisms including valve mechanism permitting independent operation thereof. 85

54. In a drilling apparatus comprising a base presenting a trackway, a frame movable longitudinally thereof and transversely relative to the drill hole, drilling mechanism including hydraulic drill controlling mechanism on said frame, and frame feeding mechanism including hydraulic controlling mechanism operatively connected to said first mentioned hydraulic controlling mechanism, 90 each of said hydraulic controlling mechanisms including an independent four-way valve operable from a point adjacent said drilling mechanism. 95

55. Core drilling apparatus comprising 100 a frame, drill rod rotating mechanism carried thereon, hoisting mechanism on said frame including a drum on an axis extending transversely of the longitudinal axis of said frame, an angle engine disposed longitudinally of said frame at one side of said mechanisms with its crank shaft toward the rear end of said frame, and driving connections between said crank shaft and said rotating mechanism and drum. 105

56. Drilling apparatus comprising a frame, drill rod rotating mechanism carried thereon, hydraulic feeding mechanism carried on said frame and disposed concentric with said rotating mechanism, a hoisting 110 drum on an axis extending transversely of the longitudinal axis of said frame, an engine disposed longitudinally of said frame at one side of said mechanisms having a power shaft toward the rear end of said frame, and driving connections between said shaft and said rotating mechanism and drum. 115

57. Drilling apparatus comprising a frame presenting a feeding and rotating support carrying drill rod feeding and rotating mechanism, and upstanding drum bearings adjacent said support transversely spaced on said frame, a drum journaled in said bearings on an axis extending trans- 120 125 130

versely of the longitudinal axis of said frame and adjacent said support, and a motor disposed on said frame at one side of one of said drum bearings and operatively connected to said drum and rotation mechanism.

58. Core drilling apparatus comprising a base presenting a guideway, a frame movable longitudinally thereof and transversely relative to the drill hole, drill rod rotating mechanism mounted on said frame, drill rod feeding mechanism mounted on said frame, hoisting mechanism on said frame including a drum disposed on an axis extending transversely of the longitudinal axis of said frame in rear of said rotating and feeding mechanisms, power driving connections on said frame for said rotating mechanism and drum including an engine and change speed gearing, capstan mechanism driven through said gearing, power driven mechanism for adjusting said frame longitudinally of said trackway, and controlling mechanism for said rotating mechanism, said feeding mechanism, said hoisting mechanism, said change speed gearing and said engine including closely grouped control members accessible from a point adjacent said rotating and feeding mechanisms.

59. In a drilling apparatus, a base presenting a substantially horizontal guideway, a frame carried thereon, drilling mechanism mounted on said frame including drill feeding means, and power actuated means for shifting said frame laterally relative to said guideway, both of said means having a common source of power.

60. In a drilling apparatus, a base presenting a guideway, a frame carried thereby, drilling mechanism mounted on said frame including drill feeding means, means for shifting said frame relative to said guideway, and common hydraulic mechanism for operating both said feeding and shifting means.

45 61. In a drilling apparatus, a base, drilling mechanism carried thereby including means for feeding the drill rod upwardly or downwardly and drill hoisting means, said hoisting means including a drum arranged on an axis disposed transversely of the longitudinal axis of said base, a motor carried by said base, and means including a friction clutch disposed on an axis parallel with said drum axis for controlling rotation of said drum, said clutch including coaxial driving and driven elements and frictional means for connecting said elements.

62. In a drilling apparatus, a substantially horizontal guideway, a base carried thereby, hole drilling mechanism carried by said base including means for feeding the drill rod upwardly or downwardly and drill hoisting means, said hoisting means comprising a drum disposed on an axis trans-

verse to the longitudinal axis of said base, a motor carried by said base, and power actuated means for shifting said base laterally on said guideway and transversely relative to the hole.

70 63. In a drilling apparatus, a base, drilling mechanism carried thereby including drill rotating, means for feeding the drill rod upwardly or downwardly and hoisting means, said latter means including a drum arranged transversely of the longitudinal axis of said base, a motor carried by said base and operatively connected to said rotating and hoisting means, and power operated means for actuating said feeding means independently of said motor.

75 64. In a drilling apparatus, a guideway, a base carried thereby, a hole drilling mechanism carried by said base including drill rotating, drill feeding, and hoisting means including a hoisting drum rotatable on an axis extending transversely of the longitudinal axis of said base, a motor carried by said base and operatively connected to said rotating and hoisting means, power means for shifting said base on said guideway transversely relative to the direction of drilling, and means independent of said motor for operating said feeding and shifting means.

80 90 65. In a drilling apparatus, a frame, drilling mechanism mounted thereon including drill rod rotating, feeding and hoisting means, a motor on said frame, and variable speed transmission means disposed between said motor and rotating and hoisting means, said transmission means for said hoisting means including a manually operable friction clutch for permitting operation of said rotation means while said hoisting means remains idle.

95 100 105 66. In a drilling apparatus, a frame, drilling mechanism carried thereby including hoisting and drill rotating mechanism, a motor mounted on said frame, variable speed transmission means operatively connected to said hoisting and rotating mechanism and said motor, and capstan mechanism driven through a portion of said transmission means.

110 115 120 67. In a drilling apparatus, a frame, drilling mechanism carried thereby including hoisting and drill rotating mechanism, a motor mounted on said frame, variable speed transmission means operatively connected to said hoisting and rotating mechanism and said motor, a capstan mechanism driven through a portion of said transmission means, and a clutch for connecting said capstan mechanism to the latter.

125 68. In a drilling apparatus, a frame, drilling mechanism carried thereby including hoisting and drill rotating mechanisms, a motor mounted on said frame, variable speed transmission means operatively con-

nected to said hoisting and rotating mechanism and said motor, a capstan mechanism driven through a portion of said transmission means, a clutch for connecting said capstan mechanism to the latter, and means for controlling rotation of the capstans when released therefrom.

69. In a drilling apparatus, a frame, drilling mechanism carried thereby including 10 drill rotating, drill feeding, and hoisting means, a motor carried by said frame, transmission means between said motor and said rotating means for driving the latter selectively at different predetermined speeds, and 15 means including interlocking mechanism for preventing simultaneous application of said different speeds.

70. In a drilling apparatus, a supporting base presenting a substantially horizontal 20 guideway, a frame adjustable longitudinally of said guideway laterally toward and from the drill hole, power operated means for adjusting said frame, drill rod rotating mechanism on said frame, power operated feeding mechanism on said frame for axially 25 feeding the drill rod, a hoisting drum immediately adjacent said rotation mechanism and rotatable on an axis disposed transversely of the longitudinal axis of said 30 frame, and a motor on said frame operatively connected to said rotation mechanism and said hoisting drum.

71. In a drilling apparatus, a supporting base presenting a substantially horizontal 35 guideway, a frame adjustable longitudinally of said guideway, power operated means for moving said frame relative to said base laterally toward and from the drill hole including cooperating elements one of which is secured to said base while the other is secured to said frame, drill rod rotating mechanism on said frame, a hoisting drum immediately 40 adjacent said rotation mechanism and rotatable on an axis disposed transversely of the longitudinal axis of said frame, and a motor on said 45 frame operatively connected to said rotation mechanism and said hoisting drum.

72. In a drilling apparatus, a supporting base presenting a guideway, a frame slidably guided on said base, power operated 50 means for moving said frame relative to said base including cooperating members one of which is secured to said base while the other is secured to said frame, drill rod rotating mechanism on said frame, a hoisting drum on said frame immediately adjacent 55 said rotation mechanism and rotatable on an axis disposed transversely of the longitudinal axis of said frame, a motor on said 60 frame, and motor driven transmission mechanism on said frame including a transverse motor shaft parallel with said drum axis and operatively connected to said drum, a shaft extending longitudinally of said frame

and operatively connected to said rotation mechanism and motor shaft and extending beneath said drum, and change speed mechanism on said frame selectively connectible to drive said drum or rotation mechanism at a plurality of speeds.

73. In a drilling apparatus, a frame, drill rod rotating mechanism thereon, power operated feeding mechanism on said frame for axially feeding the drill rod during rotation thereof, a hoisting drum on said frame immediately adjacent said rotating mechanism and rotatable on an axis disposed transversely of the longitudinal axis of said frame, a motor on said frame, motor driven transmission mechanism on said frame including a transverse motor shaft parallel with said drum axis and operatively connected to said drum, a shaft extending longitudinally of said frame and operatively connected to said rotation mechanism and motor shaft and extending beneath said drum, and change speed mechanism on said frame selectively connectible to drive said drum and rotation mechanism at a plurality of speeds.

74. In a drilling apparatus, a frame, drill rod rotating mechanism thereon, a hoisting drum on said frame immediately adjacent said rotating mechanism, a motor on said frame, and motor driven transmission mechanism on said frame driving said rotation mechanism or said drum and selectively operative to drive said rotation mechanism at any of a plurality of predetermined speeds.

75. In a drilling apparatus, a supporting base presenting a guideway, a frame slidably guided on said base, means for moving said frame relative to said base, hole drilling mechanism carried on said base including drill rod rotating mechanism and drill rod feeding mechanism, hoisting mechanism on said frame including a hoisting drum, capstans mounted on said frame, a motor on said frame, and driving connections between said motor and said drill rod rotating mechanism, said hoisting mechanism, and said capstans.

76. In a drilling apparatus, a supporting base presenting a guideway, a frame slidably guided on said base, means for moving said frame relative to said base, hole drilling mechanism carried on said base including drill rod rotating mechanism and drill rod feeding mechanism, hoisting mechanism on said frame including a hoisting drum, capstans mounted on said frame, a motor on said frame, driving connections between said motor and said drill rod rotating mechanism, said hoisting mechanism, and said capstans, and means for disconnecting said capstans from said motor at will.

In testimony whereof I affix my signature.
FRANK A. HALLECK.

CERTIFICATE OF CORRECTION.

Patent No. 1,679,137.

Granted July 31, 1928, to

FRANK A. HALLECK.

It is hereby certified that error appears in the printed specification of the above numbered patent requiring correction as follows: Page 8, line 41, claim 39, strike out the words "on said frame", and insert instead the word "thereon" and in line 42, strike out the word "thereon" and insert the words "on said frame"; and that the said Letters Patent should be read with these corrections therein that the same may conform to the record of the case in the Patent Office.

Signed and sealed this 2nd day of October, A. D. 1928.

(Seal)

**M. J. Moore,
Acting Commissioner of Patents.**
